UNITED STATES PATENT OFFICE

JAMES M. DAYTON, OF TORRINGTON, CONNECTICUT

COUNTING AND INDICATING DEVICE

Application filed January 21, 1929. Serial No. 234,034.

This invention relates to improvements in counting and indicating devices, and more particularly to such type of devices as may be applied to dispensing apparatus.

One of the objects of the present invention is the provision of a compensating mechanism by which the device may be attached to any one of a number of pumps having differing lengths of stroke for the delivery of a calibrated quantity, for the purpose of compensating for this differing length of stroke.

Another object of the present invention is the provision of a driving system whereby the movements in both directions of the pump to which the device is attached may be totalized, the particular connection for this purpose being characterized by its simplicity, and the small number of parts employed.

A further object of this invention is the provision of a driving system and the employment of a fast and a slow indicating hand, movements of the pump in both directions being totalized by respective trains, the final elements of each train being coupled together for movement in unison, with the provision of adjunct trains for driving respectively the slow and the fast hands.

Still another object of this invention is the provision of a resetting means for portions of the counting and indicating device whereby such portions may be reset to a predetermined minimum quantity in a single and quick operation and by a single manipulation.

A still further object of this invention is the provision of means whereby the resetting is accomplished by a disconnection of the driving system leading to such portions of the counting and indicating device.

Still another object of this invention is the provision of a resetting mechanism for parts of the counting and indicating device which normally is without operation upon the system and is not prepared for such operation: with the inclusion of means whereby a simple manipulation will prime such resetting means for operation, while retaining the other parts in their normal position, followed by an abrupt release of the parts thereby reset so that they are quickly and imme-

dately returned to a predetermined position.

Still another object of this invention resides in the provision of fast and slow hands for indicating the quantities dispensed, with separate driving trains therefor, and an audible alarm which is actuated upon the completion of a predetermined angular movement of such indicating hand.

Other objects and features of this invention will appear in the course of the following specification and claims, taken in conjunction with the drawings which represent one illustrative form of the construction of the device embodying the present invention. In the accompanying drawings, the device is illustrated as contained within a casing adapted to be mounted upon the enclosing and supporting standard of a gasoline dispensing pump having a cylinder which usually is slightly different in diameter for different pumps of a series, with a reciprocating piston moving therein to suck and force the gasoline at each direction of movement.

In the drawings:

Figure 1 is a conventional view showing the relationship of the dispensing pump with the counting and indicating device, showing the latter from the rear with the usual supporting and containing case removed.

Fig. 2 is a view on a larger scale but similar to the showing of the rear of the indicating and counting device of Fig. 1, with certain parts broken away for clearness.

Fig. 3 is a sectional view on line 3—3 of Fig. 1.

Fig. 4 is a view of the front of the indicating and counting device.

Fig. 5 is a sectional view on line 5—5 of Fig. 11, showing parts of the operating and counting trains.

Fig. 6 is a section on line 6—6 of Fig. 11, with the parts in indicating and counting position.

Fig. 6a is a view similar to that of Fig. 6, but with the parts in a position occupied following a resetting operation.

Fig. 7 is a similar section on line 7—7 of Fig. 11, showing the rock arm which sup-

ports the "slow" hand, and parts of the resetting plunger in section.

Fig. 8 is a sectional view taken substantially on line 8—8 of Fig. 7.

Fig. 9 is a view similar to that of Fig. 7, but with the large gear of the "slow" hand removed, for greater clearness.

Fig. 10 is an edge elevation of the parts shown in Fig. 9.

Fig. 11 is a sectional view taken substantially on line 11—11 of Fig. 6.

Fig. 12 is a similar sectional view taken on the axis of the hand staff.

Fig. 13 is a detail sectional view taken substantially on line 13—13 of Fig. 6.

Fig. 14 is a detail view taken substantially on line 14—14 of Fig. 6.

According to this invention, a reciprocating pump is connected by a variable rack arm to the actuating pinion of an indicating and counting device, with means to establish a compensation between the piston stroke of the given pump and that of a standard pump by adjustment of the effect of the rack upon the pinion. This pinion is caused to operate gear trains whereby to move the counting or totalizing mechanism itself, and to move a pair of hands at differing speed ratios. For example, if the indicating dial is graduated to indicate twenty gallons, and a pump having a capacity of one gallon per stroke is employed, the "slow" hand will move around the dial by one complete revolution for each twenty complete strokes: while the "fast" hand will move around the dial once for each complete stroke. It will thus be seen that the "fast" hand furnishes a ready means for estimating the frictional parts of a gallon which are delivered by partial strokes of the pump, giving a direct indication in the illustrated example of such fractions by fifths of a quart.

The counting train is at all times connected to the actuating pinion so that any movement of the pump will result in a totalizing of such delivered quantity. On the other hand, the driving system for the indicating hands may be temporarily disconnected or broken so that the hands may be restored to zero irrespective of the position of movement of the pump. This breakage of the driving connection is accomplished by the same device which prepares and operates the resetting mechanism itself, and members are provided in such relationship to one another that the resetting is always preceded by a disconnection of the driving trains, and a full resetting is necessarily accomplished before the driving trains may be returned to operating engagement.

The arrangement of the parts permits and includes the provision of gears of large diameter having a large number of teeth for establishing the driving connections aforesaid, so that in the event of a failure of the gears to immediately and accurately mesh

upon return to appropriate driving engagement, a very small percentage of a revolution will be occupied by initial movement of the driving train before the final and accurate engagement occurs.

In the illustrated example of execution, a double-acting liquid dispensing pump has a cylinder C and a piston P moved relatively to one another by any suitable mechanism (not shown). This pump is provided with the inlet conduit I and the dispensing conduit D connected to a four-way valve V which controls the delivery of liquid through one of the valve conduits B to one end of the cylinder C, and is discharged from the other end of the cylinder through the other valve conduit B to pipe D: all in well known manner.

The piston rod R of the pump carries a transverse bracket E having lugs 10 thereon which support and permit the rotation of an adjusting screw 11 having a head 12 and bearing a traveling nut 13 which in turn supports a pivot 14 for the rack arm 15 having teeth engaging with the driving or actuating pinion 16 of the indicating and counting device, to be described hereinafter. As shown in Fig. 3, the rack 15 has a guide bar 15a fastened thereto and presenting its edge against a nose 17 of the supporting bracket 18 of the shaft for the pinion 16. A sleeve 19 on this latter shaft receives a swinging plate 20 having a pair of rollers 21 pivoted thereto to engage with the opposite edge of the guide rail 15a. The washer 22 and nut 23 cooperate in maintaining the swinging plate 20 in position and permit a free rocking of this swinging plate about the axis of sleeve 19.

In operation, as the piston rod R reciprocates, the rack 15 is translated up and down therewith, but by reason of the offset relationship of the pivot 14 with respect to the engagement of the rack teeth with the pinion 16, the rack is caused to make a slight relative rotative movement counterclockwise with respect to the axis of the sleeve 19, being at all times held in engagement with the driving pinion 16 by the operation of the rollers 21 and the nose 17 upon the guide rail 15a. During the downward movement of the piston rod R, the rack 15 makes a corresponding clockwise movement, so that the total effect upon the pinion 16 is nil. However, since the angle of the rack 15 with respect to the direction of movement of the piston rod R may be varied, a means is presented of compensating for different lengths of stroke of the piston P for the delivery of a calibrated quantity, since when the rack 15 moves solely in the direction of its length, as when the traveling nut 13 is adjacent the piston rod R, then the number of teeth which operate to rotate the pinion 16 will depend solely on the pitch of the teeth in the rack: while

when the traveling nut 13 is at the end of the screw 11 away from the piston rod R, the same movement of the piston rod R will cause a greater number of teeth on the rack 15 to move past and operate the teeth of the pinion 16: and obviously the position of the traveling nut 13 along the screw 11 will determine the axis rotation thus given to the driving pinion 16.

Obviously, the opinion 16 is rotated first in one direction and then in another by equal amounts. It is therefore necessary to provide a uni-directional drive between the actuating pinion 16 and the trains to be driven, 15 in order to add up or totalize the respective movements of the piston P and of the pinion 16 driven therefrom.

As shown in Figs. 2 and 11, the shaft 16a of the pinion 16 carries a gear 30 which 20 meshes with two gears 31 and 32 fastened respectively to shafts 31a and 32a journaled in the plate 18a which supports the bracket 18 above referred to, and which itself is mounted in spaced relationship to the back 25 plate M of the indicating and counting device by spacing and securing bolts 33. Each of these shafts 31a, 32a carries a ball or roller clutch 31b, 32b whereby to operate a further gear 34 or 35 carried by the respective other 30 member of the clutch 31b, 32b. These clutches are designed to operate in opposite directions, i. e., when the gear 30 is turned in a clockwise direction, the gear 32 meshing therewith drives its clutch 32b and therewith 35 the gear 35, while the gear 31 turns freely without driving through its own clutch member 31b. On the contrary, when the gear 30 is turned in a counterclockwise direction, the gear 32 turns freely without driving through 40 its clutch member 32b, while the gear 31 now drives gear 34 through the clutch member 31b. The two gears 34, 35 mesh together (Fig. 2) so that a movement of one of these gears is attended by a movement of the other 45 gear in the reverse direction. Such movement is permitted by the respective ball clutches 31b, 32b, so that alternately one of the gears 31, 31b is turning with its corresponding gear 34, 35 while the other gear 32, 50 31 is turning in the opposite direction to its corresponding gear 35, 34; and vice versa.

The shafts 31a, 32a pass through the rear plate M and at the opposite side of this plate carry the respective driving pinions 31d, 32d 55 (Figs. 5 and 11), which intermesh. Pinion 31d meshes with the intermediate gear 36 having the gear 37 fixed thereto, both gears turning together about a pivot pin 38 secured to the back plate M. The gear 37 in 60 turn meshes with an idler 39 fastened to the small pitch driving wheel 40 of large diameter (Figs. 6, 6a).

The pinion 32a meshes with the gear 41 which has the small diameter pinion 42 fastened thereto, which in turn meshes with the

two gears 43 and 50. The gear 43 is an idler having a small gear 44 fastened thereto to drive a further idler 45 which in turn operates a counting device represented conventionally at T, but it will be understood to provide a plurality of disks having numerals thereon for exhibition through the viewing windows 46, whereby an inspector can determine the total quantity of liquid which has been dispensed through the pump to which the device is attached.

The gear 50 is driven from the pinion 42 and is mounted for free rotation about a pivot pin 51 which forms an extension of the pivot which supports the rocker arm 52 from the front plate, and of the indicating and counting device. This gear 50 is connected by a sleeve 53 with a small-pitch gear 54.

In the front plate N is fixedly mounted a bushing 60 in which may freely rotate a sleeve 61 having a plate 62 to support the "slow" hand S (Figs. 4 and 11) on the outer side of the dial L (Fig. 11), and rigidly connected to the large diameter "slow" wheel 63 having a large number of teeth on its periphery and likewise having fixed thereto a "slow" resetting gear 64. A spindle 65, rotatable within the sleeve 61, is fixedly connected to a similar large diameter wheel 66 having a large number of teeth on its periphery, and being in turn rigidly connected to the resetting "fast" gear 67: in front of the dial L, the spindle 65 carries the "fast" hand F.

It is preferred to form the large diameter gears 63 and 66 of substantially the same diameter, and to provide each of them with a respective arcuate slot 63a, 66a which respectively receive the enlarged ends 68 and 69 of the motion-limiting stops 70, 71 which are carried by pillars 72 fastened to the front plate N of the indicating and counting device. As indicated by the dotted circles 73 in Fig. 6, each of the arms 70, 71 has an aperture larger than the screw of the columns 72, 76 whereby the angle of presentation of the respective stop members 70, 71, as well as the distance from the respective column 72 to the extreme end 68, 69, may be adjusted.

The spindle 65 likewise has a hub 74 which supports a cam 75: as well as a stud pin 76 which is presented in the bracket 77 (Fig. 2) of the back plate M. The bushing 60 and the bracket 77 therefore form journals for the hand carrying parts at each end thereof, so that these parts are maintained for their rotative movement. A gong 78 is fastened in the cavity 79 of the gear plate M by a rivet 80. A heavy clapper head 81 is carried by a resilient arm 82 supported on a block 83 mounted on a pivot pin 84 of the back plate M (Fig. 2). The resilient arm 82 has an offset dog 85 which rides along the periphery of the cam 75. A coil spring 86 is connected to the arm 82 and to a pinion 88 fixed on the

rear plate M and assists in drawing the arm 82 and its clapper head 81 downward toward the gong 80. It will, however, be noted in Fig. 1 that the action of gravity upon this clapper head 81 will normally draw it downward when the dog 85 is released by the cam 75. It will further be apparent that the cam 75 turns by one rotation for each rotation of the "fast" hand F, which represents in turn the delivery of one unit quantity of liquid, and hence the gong will sound accurately at the moment that the hand F passes the zero line, or in other words, the gong will strike at each delivery of one gallon, coordinating with the hand F, and furnishing an audible indication corresponding to the visual indication of the hand F in making a revolution. It will be noted that a hole 89 is cut in the back plate M opposite the cam 75, so that these parts and the bracket 77 may be readily assembled with respect to one another.

As shown in Figs. 6, 6a, 7 and 9, the rocker arm 52 is pivoted on a pin 51 having a sleeve 90 thereon which is free to move with respect to the face plate N, but has a shifting arm 90a fastened thereto, and has an outwardly extending pin 91 carrying one end of a coil spring 92 which engages the pin 93 on the rocker arm 52 (Figs. 9 and 10), and thus constantly tends to pull this shifting plate 90a relatively in a clockwise direction with respect to the rocker arm 52. The shifting plate 90a supports the pivot 94 of a wheel 95 having small-pitch teeth on its edge and meshing at all times with the similar wheel 52 pivoted about the pin 51. The rocker arm 52 has a slot or large opening 96 therein which permits the pivot 94 to move relatively to the rocker arm 52, as determined by the movement of the shifting plate 90a. A stop 97 is fastened upon the rocker arm 52 to engage with the cylindrical sleeve 98 of the wheel 95, and thus limit the movement of the latter toward the large wheel 66.

The rocker arm 52 itself is drawn in a counter-clockwise direction by a coil spring 99 engaging a pin 100 on the face plate N; but is limited in its movement by an adjusting screw 101 having a lock nut 102, and engaging in an upstanding bracket 103 formed on an angle member 104 having a slot 105 therein to guide the rocker arm 52 in its movements. It is apparent that the joint operation of the adjusting screw 101 in respect to the rocker arm 52, and of the stop plate 97 with respect to the wheel 95, is to prevent the forcing of this wheel 95 into engagement with the wheel 66 with an excessive pressure; and to prevent the hammering or mutilation of the small teeth during the movement incidental to the re-meshing of these parts following a resetting operation.

The resetting mechanism comprises a finger-actuated push button 110 which is formed with a threaded end 111 to engage in a sliding

bushing 112 which moves in a supporting block 113 fastened to the face plate N by a screw 114. The central part of this block is cut away as at 115 to permit the movement of a T-shaped thrust member 116 (Fig. 14), which has the arm 117 guided between the block 113 and the face plate N, and an upstanding arm 118 which wipes along the adjacent edge of the rocking pawl 119 having the hook 120 and the operating cam portion 121; and which is constantly urged in a counterclockwise direction about its pivot pin 122 in block 113 by the spring 123. The third arm 124 of the T-shaped member 116 is connected to a spring 125 engaging a pin 126 on the face plate N, and constantly tends to pull the T-shaped member 116, together with the bushing 112, so as to return it against the manual operation of the button 110.

A stem 127 is relatively slidable in the bushing 112 and has a pin 128 engaging in a slot 129 of this bushing to limit the relative movement of the stem 127 to the length of the slot 129, this slot being closed at the end of the bushing 112 by the T-shaped plate 116 fixed to the bushing 112. The stem 127 carries at its other end, i. e., the end adjacent the hand staff, a plunger 130 which slides in a portion 131 of the block 113 (Fig. 7), while a relatively heavy coil spring 132 is located around the stem 127 and between the shoulder of plunger 130 and the T-shaped plate 116. A pin 133 holds the stem 127 and plunger 130 fixedly together, and is continued upward and downward (Fig. 8) so that it may be engaged by the hook 120 of the detent or latching device 119 on the one hand, and is guided by a slot 134 in the face plate N on the other hand, whereby to prevent a rotation of the plunger 130 about the axis of the stem 127. Pivoted by a pin 135 to the end of the plunger 130 is a connecting link 136 which has a slot 137 at its other end to receive the pin 138 on the rocker arm 52, so that upon movement of the plunger 130 toward the right in Fig. 7, the link 136 will move the rocker arm 52 whereby to disengage the wheel 95 from the wheel 63 (Fig. 7) and the wheel 40 from the wheel 66 (Fig. 6a), thus freeing the wheels 63 and 66 from actuation through their respective driving trains, and at the same time removing any restraint against the movement of the wheels 63 and 66 by any other means.

Likewise fastened in the face plate N is a pivot 140 upon which is pivotally mounted the lever 141 having a detent finger 142 fixed thereto. The lever 141 has an enlarged end 141a with two apertures 143, 144 therethrough to receive the respective coil springs 145, 146 connected at one end to the respective resetting segments 147, 148, and each having a large reaction shoulder 149 against which the lever extension 141a may operate.

The resetting segments 147, 148 are mount-

ed on the pivot 150 fastened to the face plate N, and are each provided with teeth to engage with the respective resetting gears 67, 64 (Figs. 6a, 7 and 12).

In Figs. 4 and 11, it is clearly shown that the back plate M and the face plate N are held rigidly in spaced relationship one to another by pillars 160 having reduced ends passing through apertures in the respective plates and riveted over to prevent accidental separation of these parts after assembly. The dial L is similarly held in spaced relationship to the face plate N by spacing collars 161 and screws. This dial itself is protected by a gear G carried by the enclosing jacket J which protects the entire mechanism. It will be understood that normally the back plate M is formed with an extended flange 162 having apertures therethrough by which the device may be fastened onto the customary cast-iron standard of the dispensing pump. It is likewise preferred to provide a hopper-shaped guard 163 around the push-button 110, so that an accidental contact with the push-button 110 will not result in a resetting operation of the device.

The operation of the device is as follows:

As the pump rod R moves up and down, with a stroke adjusted by a calibrating screw S, it delivers a unit quantity, say one gallon, for each stroke. A right-angled triangle is in effect formed by a line representing the direction of movement of the piston rod R, a line at right angles thereto representing the axis of the adjusting screw 11 and passing through the pivot axis 14, with a hypotenuse representing the line joining the pivot point 14 to the point of engagement of the rack 15 with the pinion 16. The screw 11 is turned and therewith the pivot point 14 shifted until the hypotenuse of this triangle is equal substantially to a maximum predetermined movement for the piston P. In other words, when the piston P is making this maximum movement, the rack 15 moves up and down in a straight line in parallelism with the movement of the rod R, but as the movement of the piston P is shortened by the set screw S, the pivot point 14 is more and more offset from this straight line position. In this way, the calibrated movement of the piston P for one gallon will cause a movement of the rack 15 in the direction of its own length, which is equal to the predetermined maximum, and thus cause at all times a unit rotary displacement of the pinion 16.

This rotation of the pinion 16 is transmitted through the double clutches as continual movements of the two pinions 31d, 32d always in the same direction, each for each. The pinion 31d operates through a gear train 36, 37, 39 to move the fine toothed large wheel 40 and thereby the fine toothed wheel 66 and thus to move the fast hand F: the gear train ratios are so selected for the desired units of

delivery that the fast hand F makes one full and exact revolution for each unit delivery from the pump cylinder C, while at the same time the cam 75 makes a full revolution, and the clapper 81 sounds the gong 78 at the instant that the fast hand F returns to zero.

At the same time, the pinion 32d drives a gear train and operates the totalizing mechanism T to indicate the total number of units dispensed through the pump: and further this pinion 32d operates a further gear 50 which in turn drives through fine toothed gears 54 and 95, the other fine toothed wheel 63, and thus moves the slow hand S. It is preferred to form the gear ratios of this drive train such that the slow hand makes one revolution for a dispensed quantity well above the usual maximum of delivery to a single customer, for example twenty gallons: since in this way the customer receives a direct indication of the total number of gallons which have been delivered to him. It will be understood that during the time that the slow hand has moved from a zero position to a position of eighteen gallons, for instance, the fast hand has made eighteen complete revolutions and the gong 78 has been sounded eighteen times.

During this movement of the hands, the gears 64 and 67 have been rotated therewith, and have operated upon the resetting segments 148, 147 to move two sectors in a clockwise direction in Figs. 6 and 6a to the position shown in Fig. 6. During this movement, the resetting springs 145 are slightly tensed so that the detent 142 will ultimately engage these segments and hold them in the position shown in Fig. 6. The engaging surfaces of the detent 142 and of the segments 147, 148 may be constructed to occasion a withdrawal of the segments from any engagement with their respective gears 64, 67.

After completing a desired delivery to a customer, and it is desired to reset the hands and associated mechanisms to zero so that a dispensing operation may be begun for a new customer, the thumb button 110 is depressed. As a result of this single operation, the gear trains driving the fast and slow hands are disconnected and these hands are returned immediately and positively to a zero position, one independently of the other, and the parts are so disposed that this return is so produced that no partial operation of the button 110 will cause a partial return of either or both of the hands to a partially restored position. The way in which this is effected is as follows:

Normally, the returning sector 147 for the fast hand is held free of the gear 67 of this hand by the detent 142: and both the turning sectors 147, 148 are without spring tension from their springs 145, 146. The fine toothed wheel 40 is in mesh with the fine toothed wheel 66, and the fine toothed gear 95 is in mesh with the fine toothed wheel 63.

As the button 110 is depressed, the plate 118 compresses the spring 132, but for the moment the plunger 130 is held immovable by the engagement of the pin 133 beyond the hook 120. At the same time, the plate 118 causes a rocking of the lever system 141, 142, 141a and thus releases the sector plates 147, 148 and brings tension upon the returning springs 145, 146. All of this has occurred without any movement of the plunger 130, and hence without any restoring of any of the indicating parts.

Upon a slight further pressure of the button 110, the plate 118 forces the hump 121 (Fig. 6) of the detent 119 in a clockwise direction, thus releasing the hook 120 from the pin 133, and permitting the plunger 130 to be forced toward the right by the spring 132. It will be noted that preferably the two large toothed wheels 63 and 66 have been held against return by the action of their respective driving trains and the ball clutch members 31b, 32b. The movement of the plunger 130, however, causes a relative endwise movement of the link 136, at first freely with respect to the pin 138, and then a sudden and abrupt clockwise movement of the rock arm 52 about its pivot 51, thus disengaging the fine toothed large wheel 40 from its meshing wheel 66; and of the fine toothed gear 95 from its meshing wheel 63. The sectors 147 and 148 are now free to drive the respective gears 67 and 64 and thus to restore the large toothed wheel 63, 66, together with the hands F and S and the cam 75 to the zero position. As the respective gears approach this position, the stop spring arms 70, 71 bring their detent ends 69 into the slots 66a, 63a, and finally bring the hands F, S to a standstill exactly at the zero position. It will be noted that this has occurred almost instantaneously: and so quickly that the operator does not have time to relieve his finger from the button 110 before the resetting has occurred.

After resetting, when the button 110 is released, the plate 118 travels back again by the action of the spring 125, and the residual tension in the springs 145, 146 causes the lever system 141, 142, 141a to return with the plate 118. The pin 128 is likewise engaged by the plate 118 and the plunger 130 and its link 136 are pulled back, permitting the return of the rock arm 52 by the action of its spring 99, until the rock arm 52 comes against the stop 101, and the driving gears are again in mesh.

It will be noted that the fine toothed large wheels 40, 66 enter positively into mesh at not greater than 1/260th of a revolution, assuming that each gear has 260 teeth: this representing an error of less than 1/4th of one percent for the indication given by the first hand. Likewise, a similar distance is the maximum of error for the slow hand,

since the gear 95 is spring pressed by spring 92 into engagement with the large wheel 63. If the tops of the teeth in the large wheel 63 and the fine toothed gear 95 should chance to come opposite each other in returning toward meshing, this is for the moment absorbed by the spring 92: but upon a slight movement of the driving gear 54 and hence of the gear 95, the parts move quickly into meshing relationship.

The stop 101 regulates the distance between the axis of the large wheels 50 and 66 so that they mesh exactly: while the plate 97 provides for a similar maintenance of the meshing relationship of the gear 95 with the wheel 63.

It will be noted that during the entire resetting operation, the various gear trains up to and including the large wheel 40 and the fine toothed gear 95 are continuously connected to the driving system from the pinion 16: and that the totalizing device T continues to add up quantities dispensed, even though such quantities may not be indicated by the hands S and F and the gong 78: in other words, an operator cannot defraud the owner of the pump by dispensing liquid with the button 110 continuously pushed in.

What I claim as new and desire to secure by Letters Patent is:

1. In a device of the class described, a member adapted to be attached to any one of a number of pumps having differing lengths of stroke for the delivery of a calibrated quantity so that the member is moved linearly in proportion to the movement of the pump, a pinion, a rack meshing with said pinion, means connecting said member and said rack so that the rack is moved with said member to rotate said pinion, and means to adjust said rack angularly with respect to said linear movement.

2. In a device of the class described, a rack adapted to be attached to any one of a number of pumps having differing lengths of piston stroke for the delivery of a calibrated quantity so that the rack is moved linearly in proportion to the movement of the pump piston, a pinion meshing with said rack, means for connecting said rack to a selected one of said pumps so that the rack is moved to rotate said pinion, and means to adjust said rack angularly with respect to said linear movement.

3. In a device of the class described for employment with any one of a number of pumps having differing lengths of piston stroke for the delivery of a calibrated quantity and each having a member reciprocated in proportion to the piston movement, the combination of a bracket connected to said member and extending transversely of the direction of movement of said member, a pivot mounted on said bracket, a rack connected to said pivot, a pinion, and a swinging rock

arm pivoted coaxially with said pinion, said arm having guide members for the movement of said rack whereby to maintain said rack in mesh with said pinion.

5. A device as in claim 3 including means for moving said pivot to and securing it at different points of said bracket.

10. A device of the class described for employment with any one of a number of pumps having differing lengths of piston stroke for the delivery of a calibrated quantity, including a bracket connected to and reciprocated by the pump piston so that its linear movement is proportional to the piston movement, 15 a rack, a pivot connection on said rack, a pinion meshing with said rack, means for securing said pivot connection to said member at varying distances from a line passing through the pinion axis and parallel to the 20 line of said linear movement, and a swinging rock arm pivoted coaxially with said pinion, said arm having guide members for the movement of said rack whereby to maintain said rack in mesh with said pinion while 25 moving with said member and turning about the axis of said pivot connection regardless of the position of said pivot connection on said member.

6. In a device of the class described for 30 employment with any one of a number of pumps having differing lengths of piston stroke for the delivery of a calibrated quantity and each having a member reciprocated in proportion to the piston movement, the 35 combination of a bracket rigidly secured to said member and extending transversely of the direction of movement of said member, a pivot, means for supporting said pivot on said bracket at any one of a number of points 40 on said bracket at differing distances from said member, a rack connected to said pivot, a pinion, and a swinging rock arm pivoted coaxially with said pinion, said arm having guide members for the movement of said rack 45 whereby to maintain said rack in mesh with said pinion.

In testimony whereof, I affix my signature.
JAMES M. DAYTON.
